UNITED STATES PATENT OFFICE.

CARL KROPP, OF DEUBEN, NEAR DRESDEN, GERMANY.

AIR-PROPELLER AND THE LIKE.

1,194,037.

Specification of Letters Patent.

Patented Aug. 8, 1916.

Application filed July 3, 1914. Serial No. 848,752.

To all whom it may concern:

Be it known that I, CARL KROPP, a citizen of the German Empire, and resident of Deuben, near Dresden, in the Kingdom of Saxony and German Empire, have invented certain new and useful Improvements in Air-Propellers and the like, of which the following is a specification.

My invention relates to a device applicable to the propulsion of aeroplanes, and particularly to a device of the type in which lifting surfaces arranged within a drum are alternately contracted or folded and expanded or spread out. As constructed hitherto, such devices effect the contraction of the lifting surfaces after their working stroke, either by means of springs connected with rollers carrying one end of the respective surfaces, or by means of a special operating device connected with the rollers carrying the one end of the respective surfaces and serving to wind up these surfaces after their working stroke. Each of these old constructions is deficient in that it fails to insure the reliable operation which is required in the case of an aeroplane; in the one construction, the proper operation of the device depends on the good quality and condition and on the proper strength of the springs, in the other construction a separate complicated actuating device is necessary for each driving element consisting of a drum, which in devices of the present type is always used in conjunction with another element and is provided in a plurality of elements.

The device invented by me affords an absolutely reliable operation, the contraction and expansion of the lifting members or surfaces occurring automatically as the drum rotates, without any special additional mechanism for effecting such expansion and contraction. For this purpose, the lifting members are located between the peripheries of two drums one of which is located within the other, and the desired operation is obtained simply by rotating these drums on their respective axes, at the same rate of speed. The inner drum is arranged eccentrically within the outer drum, and that portion of the periphery of the inner drum which moves downward during the operation, extends to or beyond the axis of the outer drum.

In the accompanying drawings I have shown the application of my invention for

its preferred purpose, viz.: that of exerting a lifting action, Figure 1 being a side elevation of a driving element, Fig. 2 a horizontal section through the center of Fig. 1; Fig. 3 is a diagrammatic rear elevation of an aeroplane (of the flying boat type) provided with two driving elements according to my invention, this view being on a smaller scale than Figs. 1 and 2; and Fig. 4 is a detail view (upon a larger scale) showing the driving mechanism of the construction represented in Fig. 3, as seen from above.

Within the drum 1, consisting of two rims 2, 3, hubs 4, 5, spokes 6, 7 connecting the hubs with the respective rims, and rods 8 connecting one rim with the other, there is arranged a smaller drum 9, consisting in a like manner of rims 10, 11, hubs, 12, 13, spokes 14, 15, and longitudinal rods or braces 16. The number of rods 8 is equal to the number of rods 16; the said rods are arranged in pairs each comprising a rod 8 and a rod 16, and the two rods of each pair are connected by a lifting member 17 made of textile fabric or other suitable flexible material. The hubs 4, 5 are journaled upon alining axles 19, 20 secured to the frame 18, and said axles are connected by horizontal stays 21, 22 respectively with an axle 23 parallel to the other axles and supporting the hubs 12, 13. Transmission chains 24, 25 connect the hubs 4 and 5 with the hubs 12 and 13 respectively, the sprockets engaged by said chains having the same number of teeth, so that the two drums will have the same rotary speed or angular velocity. The hub 5 also carries another sprocket 26 engaged by a driving chain 27. To the inner ends of the hubs 12, 13 of the drum 9 are secured propelling screws or propellers 28, 29 respectively of opposite pitch and so constructed as to force air inwardly when the drums are rotating and to deliver such air to the lifting members 17.

When the drums 1, 9 are rotated by the chain 27, sprocket 26, and chains 24, 25, each of the lifting members 17, considered as a whole, swings about an axis which lies at the intersection of the horizontal central plane of the device and of the plane containing the two rods 8, 16 of that particular lifting member. In Fig. 1 this axis is designated as D, and two dotted lines indicate the planes of two pairs of rods 8, 16.

It will be obvious from Fig. 1 that the rods 8 and the outer ends of the lifting

100

95

105

110

members 17 secured thereto, which are just in line with the corresponding inner rods 16 in the central position shown at the extreme left in Fig. 1, will, on account of their 5 greater linear speed, gain on or travel ahead of, the corresponding inner rods 16 which carry the inner ends of the respective lifting members 17. This lead of the outer end of the lifting members is quite considerable 10 even shortly after the lifting member has risen from the central position shown at the extreme left in Fig. 1, which is the fully folded or contracted position. The result is that even shortly after passing this point 15 the members 17 tend to exert a lifting action, forming as it were pockets to catch the air and carry it around. The lifting surfaces or members 17 therefore will exert no lifting action only at a small portion of the 20 device, say about the portion which lies to the left of a vertical plane passing through the axis D.

Placing the axis of movement of the lifting members at one side, as at D, (instead 25 of centrally) presents another important advantage. That is to say, the linear speed of the inner edges (rods 16) of the lifting members 17 at the points where the greatest efficiency is obtained (extreme right in Fig. 30 1), is materially greater (owing to the greater distance or radius) than if the said axis were for instance coincident with the axis of the drum 1. The result is that the center of pressure of the air resistance is 35 brought as far as possible from the center of the lifting members, and thus I obtain a very efficient lifting action of said members.

The screws or propellers 28, 29 may be arranged outside of the two drums 1, 9 instead 40 of inside as shown. Provision may also be made for stopping one or the other of these screws, so that the one screw remaining in operation will have the function, not only of forcing air into the drums 1, 9, as explained 45 above, but also of propelling the body (aeroplane) which carries the device.

In Fig. 3 I have shown the general arrangement of an aeroplane (flying boat) provided with my improved driving or propelling device. The frame 18 is secured to the boat hull 31 provided with landing wheels 30 and carrying at each side one or more pairs of driving elements 1, 9. Within the hull 31 is arranged the main shaft 32, 55 operated say by an internal combustion motor and transmitting its motion by means of a chain 33 to a sprocket wheel 34 and to its shaft 35. The latter actuates a differential gearing 36; this on one side operates a spur-wheel 37 mounted loosely on the shaft 35 and meshing with gear 38 on the shaft of which is also secured a sprocket 39 operating the chain 27, while on the other side of the differential gearing there is a sprocket 60 40 likewise loose on the shaft 35. On the

hubs of the spur gear 37 and of the sprocket 40 I provide brake drums 41, 42 respectively coöoperating with brake bands 43, 44 respectively. The shaft 35 further carries the main propeller 45 of the aeroplane or flying boat. 70

With the arrangement shown in Figs. 3 and 4, if a current of air should strike only one of the pairs of driving elements 1, 9, and impede or retard the operation of this pair, an equalization is obtained immediately 75 by the automatic action of the differential gearing which in this case will cause the corresponding pair of elements 1, 9 on the other side of the aeroplane to be accelerated or speeded up. This action, to wit, the acceleration of one pair of lifting or driving elements relatively to the other pair driven by the same differential, may be obtained at any time at the operator's will, by applying one of the brakes 43 or 44. The transverse 80 or lateral stability of the aeroplane is therefore very great, both as to automatic control and with reference to mechanical control by the operator.

While I have described my invention with 90 especial reference to its application to aircraft, it will be obvious that the device may be used in other cases where it is desired to exert a propelling action on a fluid medium. Furthermore it will also be evident that the 95 device is reversible in function, that is to say, if the members 17, instead of acting upon a fluid, are exposed to the impact of a fluid current directed transversely to the drum axis, the device will operate as a 100 motor.

Various modifications may be made without departing from the nature of my invention as set forth in the appended claims.

I claim as my invention:

1. A device of the class described, comprising two drums of different diameters, one located within the other eccentrically, a connection between said drums whereby they are compelled to rotate in unison, and flexible connecting members or surfaces extending from one drum to the other and adapted to be expanded and contracted alternately as the drums rotate. 105

2. A device of the class described, comprising two drums of different diameters, one located within the other eccentrically and reaching at least to the center of the larger drum, a connection between said drums whereby they are compelled to rotate in unison, and flexible connecting members or surfaces extending from one drum to the other and adapted to be expanded and contracted alternately as the drums rotate. 110

3. A device of the class described, comprising two rotary members, one located eccentrically within the other, a connection between said members whereby they are compelled to rotate in unison, and flexible connecting members or surfaces extending from 115 120 125 130

one rotary member to the other and adapted to be expanded and contracted alternately as said members rotate.

4. A device of the class described, comprising two rotary members, one located eccentrically within the other, a connection between said members whereby they are compelled to rotate in unison at the same angular velocity, and flexible connecting members or surfaces extending from one rotary member to the other and adapted to be expanded and contracted alternately as said members rotate.

5. A device of the class described, comprising two drums of different diameters, the smaller located eccentrically within the larger, and their axes being parallel, each drum comprising hubs, rims, spokes connecting the rims with the hubs, and longitudinal

20 rods connecting the rims of the same drum,

an operative connection between the two drums to compel them to rotate in unison, and flexible members or surfaces having their respective ends secured to corresponding longitudinal rods of the two drums.

25

6. A device of the class described, provided with members arranged to rotate about parallel axes, connecting members of flexible material extending from one rotary member to the other and adapted to be expanded and contracted alternately as said members rotate, and means for directing a fluid toward said connecting members.

30

In testimony whereof, I have signed this specification in the presence of two subscribing witnesses.
